UNITED STATES PATENT OFFICE.

STEWART McCUTCHEON, OF SUPERIOR, WISCONSIN.

STREET-SPRINKLING DEVICE.

1,076,594.

Specification of Letters Patent.

Patented Oct. 21, 1913.

Application filed August 21, 1911. Serial No. 645,133.

To all whom it may concern:

Be it known that I, STEWART McCUTCHEON, a citizen of the United States, residing at Superior, in the county of Douglas and 5 State of Wisconsin, have invented certain new and useful Improvements in Street-Sprinkling Devices, of which the following is a specification.

My invention relates to an improvement 10 in street sprinkling devices, and the object is to provide a pipe having perforations therein at the highest point of the road bed in such a manner that water passing through the openings will wash the road surface, and 15 at the same time moisten it to take the place of the ordinary sprinkler.

A further object is to provide a device of 20 the character described, which is inexpensive to install, and which when installed is held in the bed of the road, and at the same 25 time protected from traffic.

The invention still further consists in 30 certain novel features of construction and combinations of parts which will be hereinbelow after fully described and pointed out in the 35 claims.

In the accompanying drawings: Figure 1 30 is a transverse vertical section through the pipe and guard-plate showing them in position in the street, Fig. 2 is a top plan view of the pipe, Fig. 3 is a top plan view of the guard plate, and Fig. 4 is a transverse vertical section of a road bed showing the position at which the device would be mounted 35 therein.

A, represents a pipe of ordinary construction. This pipe on an ordinary road would 40 be probably four inches (4") in diameter, although the size might vary as requirements demanded.

Two rows of openings 1, 1, are formed in the upper wall of the pipe, and these rows are preferably staggered, as shown in Fig. 2. Pipe A is mounted in the bed of the 45 road preferably at the highest point, in such a manner that that portion of the wall having the holes therein projects about one-half of an inch ($\frac{1}{2}$ ") above the surface of the road bed, and the pipe will be held by reason of the bed being compacted therearound. As a further means of protecting 50 the pipe, the guard-plate B is provided; this is made from sheet metal bent so as to

fit closely against the projecting upper part of the pipe, and is held in place by counter-sunk set screws 2, passing through the holes 3, which are provided at intervals along the guard-plate. A row of openings 4 is formed on each edge of the guard-plate, and these rows are staggered in the same manner as the rows in the pipe, so that they will be in alignment with the openings formed in the pipe, and to all intents and purposes when the guard-plate is secured to the pipe, each pair of registering openings will be one continuous bore. The projecting edges 5, 5, of the guard-plate rest upon the surface of the road bed and form a further support for the pipe.

In operation the pipe A is connected to any suitable source of water supply, which may be a hydrant, or even a water-main, and the water is turned in pipe A. As the pipe fills, the water will pass out through openings 1 and 4 in the pipe and guard respectively, and flow down over the surface of the road bed to the gutters, as indicated by the arrows in Figs. 1 and 4, from whence it would pass into the sewers and be carried away. In this manner, it will be seen that I have provided a device which is simple and inexpensive to manufacture, being composed of an ordinary iron pipe and a sheet metal guard-plate, and one which is supported against being forced into and also from being withdrawn accidentally from the road bed.

Having fully described my invention, what I claim as new and desire to secure by Letters Patent, is:—

1. A street sprinkling and flushing device, composed of a pipe circular in transverse section having openings through the wall thereof as an outlet for the water, a guard plate for protecting the pipe, said guard plate having projecting edges constructed to rest on the surface of the street, and means for securing the guard to the pipe after the pipe has been laid in the road bed.

2. A street sprinkling and flushing device composed of a pipe circular in transverse section having openings therethrough, a guard-plate shaped to fit over the upper circumference of the pipe, said guard-plate provided with openings adapted to register with the openings in the pipe and having

projecting edges constructed to rest on the surface of the street, and means for securing the guard-plate to the pipe after the pipe has been laid in such a manner that the pipe is supported by the guard-plate and is held from being pressed into the road-bed.

In testimony whereof I affix my signature, in the presence of two witnesses.

STEWART McCUTCHEON.
